FREQUENCY MODULATION

Dominic M. Kaltenbacher, Bloomington, Ind., assignor to Radio Corporation of America, a corporation of Delaware

Application May 29, 1942, Serial No. 445,008

8 Claims. (Cl. 179—171.5)

This invention relates generally to sound detection apparatus and particularly to improved means for converting sound waves into frequency modulated electric currents, radiating the frequency modulating currents as radio waves, detecting at a remote point the frequency modulated radio waves, and reproducing the received signals as sound waves.

While various methods for sound detection have been utilized in the past, this invention provides a simple and improved means for frequency modulating an oscillatory circuit in response to sound waves impinging upon a conventional acoustic diaphragm. The diaphragm is arranged to drive a magnetic core and a capacitor electrode to provide simultaneous variation of an inductor and a capacitor in the oscillation circuit of a thermionic tube oscillator. Any conventional type of oscillator circuit may be used and provision may be included for adjusting the carrier frequency thereof. Preferably the output of the oscillator should be coupled through a suitable high frequency amplifier designed to amplify efficiently the frequency band required. The output of the amplifier may be coupled to a transmission line or to an antenna for radiating frequency modulated high frequency waves. In either instance, a suitable receiver for frequency-modulated high frequency signals should be provided for reproducing the frequency modulated signals as sound waves. A plurality of such sound pickup devices may be employed, and operated on the same or different carrier frequencies, for reception by any suitable frequency modulation receiver equipment.

Among the objects of the invention are to provide a new and improved means for converting sound waves into corresponding simultaneous variations of inductive and capacitive reactance. Another object of the invention is to provide a new and improved means for detecting sound waves by means of a suitable acoustic diaphragm, varying simultaneously the inductive and capacitive reactance of a tuned oscillatory circuit in response to the sound waves, and transmitting a frequency modulated signal in which the modulation is derived from the variable reactance device. A still further object of the invention is to provide a new and improved means for detecting sound waves by a suitable acoustic diaphragm, simultaneously, and in the same sense, varying thereby the inductive and capacitive reactance of a tuned oscillatory circuit, and transmitting the resulting frequency modulated

signals, in which the modulation is derived from the sound waves.

The invention will be described by reference to the drawing in which Figure 1 is a schematic circuit diagram of one embodiment of the complete system; and Figure 2 is a schematic diagram of a modification thereof.

Referring to the drawing, sound waves S drive the diaphragm 12 in the direction indicated by the arrow. A thermionic tube oscillator 1 is supplied with cathode, control electrode and anode operating voltages in any conventional manner. The control electrode circuit includes a resonant circuit comprising the inductor 2 and the capacitor 3 connected in parallel and designed to resonate at the desired carrier frequency. The tube anode circuit includes a parallel resonant circuit comprising the inductor 4 connected in parallel with the capacitor 5. A variable capacitor 8 may be connected in parallel with the first capacitor 5 to adjust the anode circuit to resonance with the control electrode circuit, whereby the complete oscillator circuit corresponds to the conventional tuned-grid, tuned-plate oscillator well known in the art. A movable magnetic core 6, which may be of the powdered iron type, and a movable capacitor electrode 7 are both rigidly connected to the diaphragm 12 and arranged to oscillate coaxially with the axes of the inductor 4 and the capacitor 5. Thus, movement of the diaphragm 12 in response to detected sound waves provides simultaneous variation of the inductive and capacitive reactance of the tuned anode circuit. The simultaneous variation of both inductive and capacitive reactance provides a highly efficient method of frequency modulating an oscillator circuit. Oscillations derived from the oscillator circuit are coupled through the capacitor 9 to a suitable high frequency band pass amplifier 10, and are radiated as frequency modulated radio waves by means of the antenna 11. At any desired remote point the frequency modulated signals are received on the antenna 12 of the frequency modulation receiver 13, which may be of any type well known in the art. The received signals are then reproduced as sound waves by the reproducer 14.

It should be understood that any desired number of sound pickup circuits may be utilized, and that frequency modulated signals therefrom may be radiated at the same or different frequencies. It should also be understood that the signals may be transmitted from the amplifier 10 to the receiver 13 by any suitable high frequency trans-

mission line. If the apparatus is to be utilized for the detection of predetermined audible frequencies, the diaphragm 12 should preferably be designed to resonate thereto, and may include a suitable acoustic amplifier, not shown herein.

Figure 2 is a modification of the sound conversion device included in the circuit of Fig. 1. A conical diaphragm 12 drives a magnetic diaphragm 22 in response to sound waves received thereon. The reactance of a magnetic circuit, including a U shaped core 23 and the windings 24, is varied by the magnetic diaphragm 22 disposed adjacent the ends of the core 23. Simultaneously the magnetic diaphragm 22 varies the capacitive reactance of a circuit including the magnetic diaphragm 22 and a capacitor electrode 25 disposed adjacent and parallel thereto. The magnetic and capacitive circuits may be electrically connected either in series or parallel, as desired. Preferably, the variations of inductive and capacitive reactance should be of approximately the same magnitude in response to sound waves, to provide a device of maximum sensitivity and efficiency.

I claim as my invention:

1. In apparatus for converting sound waves into timing modulated currents, a multi-electrode thermionic tube, a tuned oscillatory circuit including a variable inductance and a capacity formed by at least two conducting elements between which effective capacity exists which capacity is variable, the said variable inductance and variable capacity being in said oscillatory circuit and coupled to electrodes of said tube, means for causing oscillatory current to flow in said oscillatory circuit, and means responsive to said sound waves for simultaneously varying said variable inductance and said variable capacity formed by said elements to change the tuning of said oscillatory circuit to modulate the timing of the oscillatory energy flowing in said oscillatory circuit.

2. Apparatus of the type described in claim 1

including load means coupled to said oscillatory circuit.

3. Apparatus for converting sound waves into frequency modulated current including a thermionic tube oscillator, a tuned oscillatory circuit

5 including an inductor and a capacitor element connected to said tube, and means responsive to said sound waves including a magnetic core and a second capacitor element simultaneously movable with respect to said inductance and said first capacitor element respectively for varying simultaneously said inductance and the capacity formed by said capacitor elements for frequency modulating said oscillator.

10 4. Apparatus of the type described in claim 3 including a diaphragm responsive to said sound waves and operating means connecting said diaphragm to said core and said second capacitor element.

15 5. Apparatus of the type described in claim 3 including load means coupled to said oscillator.

6. Apparatus for converting sound waves into frequency modulated currents including a thermionic tube oscillator, a tuned oscillatory circuit

20 including an inductor and a capacitor element connected to said tube, and means responsive to said sound waves including a magnetic core and a second capacitor element simultaneously movable with respect to and coaxial with said inductance and said first capacitor element respectively for varying simultaneously said inductance and the capacity formed by said capacitor elements for frequency modulating said oscillator.

25 7. Apparatus of the type described in claim 1 including an adjustable capacitor connected in said oscillatory circuit for adjusting the carrier frequency of said apparatus.

30 8. Apparatus of the type described in claim 3 including an adjustable capacitor connected in said oscillatory circuit for adjusting the carrier frequency of said apparatus.

DOMINIC M. KALTENBACHER.
